ABRASIVE WHEEL

Malcolm M. Boucher, Tacoma, Wash., assignor to
Behr-Manning Corporation, Troy, N. Y., a cor-
poration of Massachusetts

Application March 2, 1939, Serial No. 259,312

1 Claim. (Cl. 51—194)

The invention relates to abrasive wheels, and with regard to its specific features to a joiner for joining the ends of a piece of coated abrasive to form the covering for a polishing wheel or the like.

One object of the invention is to provide a polishing wheel whose abrasive action is substantially uninterrupted. Another object of the invention is to provide a simple device for covering a polishing wheel with coated abrasive material without leaving a joint which will bump the work as the work is held against the polishing wheel. Another object of the invention is to provide a simple abrasive band joiner facilitating the covering of polishing wheels with coated abrasive material. Another object of the invention is to provide an improved polishing wheel of the expandable type. Other objects will be in part obvious or in part pointed out hereinafter.

The invention accordingly consists in the features of construction, combinations of elements, arrangements of parts, and in the several steps and relation and order of each of said steps to one or more of the others thereof, all as will be illustratively described herein, and the scope of the application of which will be indicated in the following claim.

In the accompanying drawing illustrating one of many possible embodiments of the mechanical features of this invention:

Figure 1 is an axial sectional view of an expandable polishing wheel to which the abrasive band and joiner of the present invention may be applied;

Figure 2 is an end elevation of a polishing wheel, showing an abrasive band thereon with its ends held together by the joiner of the present invention which is located in a recess formed in the wheel;

Figure 3 is a fragmentary sectional view, on an enlarged scale, of the periphery of the polishing wheel at the point where it is recessed to receive the joiner, illustrating also the joiner and a fragment of the coated abrasive material;

Figure 4 is a plan view of the joiner;

Figure 5 is an end view of the joiner;

Figure 6 is a side elevation of the polishing wheel after the coated abrasive has been placed on it, showing the joiner being inserted in the recess; and

Figure 7 is a perspective view of an anvil member, illustrating the manner of preparing the coated abrasive material for cooperation with the joiner.

Referring first to Figure 1, I have therein il-

lustrated an expandable polishing wheel. Such a wheel may comprise a cylindrical block of rubber 10 having countersunk flanges 11 and 12 located in corresponding countersunk recessed portions in the ends of the block of rubber, which is provided with a central axial bore 13. The expandable wheel may be mounted upon an armature shaft 14 of an electric motor, not shown, or the shaft 14 may be rotated in any other desired manner. The shaft 14 is shown as provided with an enlarged diameter portion 15 which abuts the flange 11. To the right of the enlarged diameter portion 15 is a cylindrical portion 16 of the shaft 14 which just fits within the bore 13. Beyond the portion 16 to the right thereof is a slightly reduced diameter portion 17 of the shaft 14 fitting a similarly reduced diameter portion 18 of the bore 13. The right-hand end of the shaft 14 is drilled and tapped and receives a bolt 20 which may be forced against a large bushing 21 which is permanently fastened to the recessed flange 12. A washer 22 is preferably interposed between the head of the bolt 20 and the bushing 21.

If now the cylindrical rubber block with its flanges 11 and 12 be placed upon the shaft 14, as shown in Figure 1, and the bolt 20 be tightened, the rubber will be squeezed together by the flanges 11 and 12 which will cause the rubber to expand. The rubber block 10 acts as a support for an endless band of coated abrasive material which is of a size to fit easily over the rubber block 10 when the bolt 20 is loosened; the bolt 20 may then be tightened which expands the rubber inside of the endless band, thus holding the band firmly in place. This makes an effective polishing wheel because the abrasive is supported by a resilient backing, yet it is firmly held to this backing and the removal of a used abrasive band and replacement thereof with a new one may be quickly accomplished.

Various expedients have heretofore been adopted for forming endless bands out of coated abrasive material, but most of these have been open to the objection of forming a seam so that the covered article has a bump in its periphery. When polishing or abrading with a rotatable abrasive article having a pronounced seam or a bump or a ridge, there is a tendency for the ridge to do most of the abrading until the abrasive grains are worn therefrom, and thereupon the underlying paper or cloth quickly wears out and the entire endless band has to be discarded before the useful life of its major portion is utilized.

Referring now to Figures 2 and 3, I first form in the periphery of the block 10 a wide but shallow groove 25 of substantially uniform depth extending from end to end of the rubber block 10, 5 with the edges of the groove 25 along cylindrical elements of the rubber block 10. Referring now to Figures 4 and 5, I provide a joiner 30 which is made from a rectangular piece of sheet metal, preferably steel, and which comprises a rectangular back portion 31 and a pair of similar turned-over front portions 32. I provide a suitable length of coated abrasive material of any desired type. This may be paper or cloth coated with any suitable abrasive, such as silicon carbide or any other hard carbide, garnet, quartz, crushed glass, alumina in any of its forms including fused alumina, emery or corundum. I select a width of the coated abrasive material which is the same as the length of the block 10, 10 or if such width be not readily available, I cut out a long strip of material of such width. I then carefully calculate the length of the abrasive material which should be equal to the circumference of the block 10 in its collapsed condition, plus 15 twice the inside length of a portion 32. I then cut the abrasive material to this length or slightly more or less. Referring now to Figure 7, I provide an anvil 35 which may consist of a piece of wood or metal, generally rectangular in shape, 20 and having a groove 36 in its upper edge, the anvil member 35 having sharp corners. This anvil member 35 is preferably of a length at least equal to the width of the coated abrasive material to be used to cover the block 10. The 25 depth of the groove 36 plus the width of that part of the upper portion of the anvil 35 which extends between the groove 36 and a side wall 37 is just slightly less than the inside length of a portion 32. I now place the end of the coated 30 abrasive material in the groove 36 and bend the abrasive material over, as shown in Figure 7. With a metal rod, the back of a knife blade or any other instrument, I then scrape off the abrasive at the line 40, which may readily be done 35 since the coated abrasive material is flexed into a right angle at this point.

The ends of the length of coated abrasive material may now be bent over to form underlapping portions 42, as shown in Figures 2 and 3. I then 40 take the coated abrasive material and place it around the rubber block 10 with the lines 40 where the abrasive has been scraped off abutting each other and with the underlapping portions 42 lying in the groove 25. I then slip the end 45 of the joiner 30 into position with the portions 32 between the underlapping portions 42 and the inside cylindrical surface of the coated abrasive material 45. Figure 6 shows the joiner 30 being slipped into position. When it is inserted 50 all the way into the groove 25, the bolt 20 can be tightened and then the coated abrasive 45 is securely locked onto the rubber block 10.

It will now be seen that the rubber block 10 has applied thereto a piece of coated abrasive 55 material which is in effect jointless. The joiner 30 fits in the groove 25 with a snug fit, as shown in Figure 3, and there is no bump or elevation or ridge in the surface of the polishing wheel. The 60 coated abrasive material may, therefore, be used for its entire useful life on all portions thereof. When it is desired to replace the abrasive band 45 with a new one, the bolt 20 may be loosened and the joiner 30 then slipped out of position and a new band quickly inserted.

It is contemplated that a great many bands can be cut to the right dimensions and have the abrasive grains scraped off in lines 40 by the apparatus shown in Figure 7 or in any other suitable manner, and then the changing of 5 abrasive bands on the polishing wheels is a matter of but a moment, using the joiner of the present invention. It will be seen that if the joiner 30 should happen to be opened up slightly so as to form anything in the nature of a ridge, 10 it can be quickly closed down by an ordinary pair of pliers or with a vise. Furthermore, the polishing action has a tendency to close the portions 32 onto the portion 31 so there is substantially no danger that a ridge will be formed in 15 the polishing wheel. I have found that the joiner made according to the present invention holds the abrasive very rigidly and there is no tendency of the coated abrasive material to come out from the joiner. Because I remove abrasive 20 material along a given line which fits over an edge of the portion 32, the coated abrasive band is substantially interlocked to the joiner 30.

One particular advantage of the present invention is that the joiner 30 locks or keys the 25 abrasive band to the rubber block or drum 10. This prevents the band 45 from slipping and avoids wearing out the drum. A specific feature of value of my joiner is that it can be made very light and in fact it can readily be made so 30 that the weight of the joiner plus the extra amount of coated abrasive in the groove 25 is exactly equal to the weight of rubber removed to form said groove, so that the wheel will be in 35 perfect balance.

Another advantage of the present invention is that an endless abrasive band can be quickly made up anywhere. I have shown how it can be made up on the drum itself and this is advantageous when a single shaft has a plurality of 40 polishing wheels because premade endless bands cannot readily be placed on the inner wheel's. So also the existence of shaft hangers is no obstacle to the application of my improved abrasive bands. In many cases I can assemble the 45 band and joiner off the wheel or drum, for example around a shaft next to the drum, and then slide them into position while the drum is collapsed.

It will thus be seen that there has been provided by this invention a method and an article in which the various objects hereinabove set forth together with many thoroughly practical advantages are successfully achieved. As various possible embodiments might be made of the 55 mechanical features of the above invention and as the art herein described might be varied in various parts, all without departing from the scope of the invention, it is to be understood that all matter hereinbefore set forth is to be 60 interpreted as illustrative and not in a limiting sense.

I claim:

A polishing wheel comprising a cylindrical rubber block, metal flanges on the ends of said block, screw means to press the flanges together, there being a recess in the periphery of the block, an abrasive band on the said periphery, a joiner in the said recess comprising a back portion and a pair of turned-over portions, the ends of the 70 abrasive band being locked under said turned-over portions.

MALCOLM M. BOUCHER.
